UNITED STATES PATENT OFFICE.

FITZ WILLIAM SARGENT, OF MAHWAH, NEW JERSEY, ASSIGNOR TO THE AMERICAN BRAKE SHOE & FOUNDRY COMPANY, OF WILMINGTON, DELAWARE, A CORPORATION OF DELAWARE.

BRAKE-SHOE.

1,218,704.

Specification of Letters Patent. Patented Mar. 13, 1917.

Application filed January 6, 1917. Serial No. 140,921.

To all whom it may concern:

Be it known that I, FITZ WILLIAM SARGENT, a citizen of the United States, and a resident of Mahwah, in the county of Bergen and State of New Jersey, have made and invented certain new and useful Improvements in Brake-Shoes, of which the following is a specification.

My invention relates to brake shoes, and particularly to that type or class in which hard metal inserts are incorporated in the body of the shoe, providing a composite wearing face therefor.

The provision of hard metal inserts in the cast body of a brake shoe necessarily weakens the same, and it is an object of my invention to provide an insert of such character that a plurality of layers of openwork ductile metal may be incorporated in the body of the shoe and thereby more than offset the weakening of the shoe by the presence of the inserts. A further object of my improved brake shoe is to so form or construct the inserts that the cast metal of the body of the shoe will flow freely thereabout. To this end, the inserts are formed as separate and distinct tapering members anchored in place by their general tapering character and by openwork reinforcing members which extend throughout the body of the shoe. The cast metal of the body of the shoe is formed around each insert and anchors the same in place, as well as securing them to the openwork reinforcing members, through the mesh of which the inserts extend. A further feature is the provision of a reinforcing member extending across the inner extremities of the insert and adjacent the back of the shoe, whereby the inserts are bound together and held rigidly in position during the time the body of the shoe is being cast therearound. This rear reinforcing member also materially strengthens the body of the shoe.

A further object is to provide a brake shoe with inserts so formed that they will be held rigidly in place even though the shoe become worn and fractured in service, each insert being provided with an offset head or a connecting bar, whereby they are anchored to the strands of the adjacent reinforcing member with which the body of the shoe is provided.

Other objects and advantages will appear as the description proceeds, wherein it is

to be understood that changes in the precise embodiment of the invention may be made within the scope of what is claimed without departing from the spirit thereof.

The preferred embodiment of my invention is disclosed in the accompanying drawings, wherein:

Figure 1 is a view in top plan of a brake shoe, portions thereof being broken away, embodying the characteristic features of my invention;

Fig. 2 is a view in transverse section taken on the line 2—2 of Fig. 1;

Fig. 3 is a detail view in perspective of the hard metal insert;

Fig. 4 is a view in transverse section of a shoe having a somewhat modified form of insert therein;

Fig. 5 is a detail view in perspective of this type of insert;

Fig. 6 is a view in transverse section of a shoe having a somewhat further modified form of insert;

Fig. 7 is a detail view in perspective of this latter type of insert;

Fig. 8 is a view in side elevation of several inserts, together with the openwork metal reinforcement prior to embodying the same in the body of a shoe.

Referring specifically to the several views, my improved brake shoe is formed with the cast metal body 10, in which is incorporated a number of hard metal inserts 11. These inserts, as illustrated in Figs. 4, 5, 6 and 7, are formed as entirely separate and distinct members, of tapering and general conical outline. These inserts are incorporated in the body of the shoe, with the smaller ends 12 terminating at the wearing face thereof. A reinforcing member 13 extends throughout the body of the shoe and is formed of superposed and spaced layers of openwork metal, the openings in the several layers, being in vertical alinement, receiving the inserts 12 therethrough. In order that the inserts and several layers of openwork metal may be rigidly held in place as the metal of the body of the shoe is cast thereabout, a supplemental reinforcing member 14 is provided and extends across the rear and larger extremities of the inserts, this reinforcing member also materially strengthening the completed shoe.

The rear and larger extremities of the inserts are provided with offset heads 15, 110

which aid in holding the inserts from becoming detached from the body of the shoe as the latter becomes worn.

In Figs. 1, 2 and 3, the offset heads of the inserts are joined so as to define connecting bars between two or more inserts, the connecting bars being relatively thin and serving to hold the inserts in proper spaced relation during the time the body of the shoe is being cast thereabout. The connecting bars, being relatively thin, however, do not interfere with the free flow of metal between the various interstices of the reinforcing members and the inserts themselves.

In some instances, I prefer to form the tapering inserts, which are of general conical outline, with longitudinally extending flutes or grooves 17. These grooves increase the space between adjacent inserts and promote the free flow of cast metal thereabout. In order to hold the several layers of the reinforcing member 13 apart, and thereby aid in the free flow of the cast metal, the said layers of openwork metal may be provided with confronting depressions or grooves 18, as illustrated in Fig. 8.

What I claim is:—

1. A brake shoe consisting of a cast metal body, a reinforcing member composed of superposed layers of openwork metal extending throughout said body with the openings in said layers of openwork metal in alinement, and a plurality of separated tapering inserts extending through the mesh of the reinforcing member and anchored thereto by the cast metal of the body of the shoe.

2. A brake shoe consisting of a cast metal body, a plurality of separated inserts incorporated therein, tapering toward the wearing face of the shoe, the inner extremities of the inserts provided with offset heads, and a reinforcing member of openwork metal incorporated in the body of the shoe and receiving the inserts therethrough.

3. A brake shoe consisting of a cast metal body, a plurality of separated inserts incorporated therein, tapering toward the wearing face of the shoe, the inner extremities of the inserts provided with offset heads, a reinforcing member of openwork metal incorporated in the body of the shoe and receiving the inserts therethrough, and a supplemental reinforcing member extending throughout the body of the shoe and across the rear extremities of said inserts.

4. A brake shoe consisting of a cast metal body, a plurality of inserts embedded therein and tapering toward the wearing face of the shoe, a reinforcing member consisting of superposed layers of openwork metal extending throughout the body of the shoe and receiving the said inserts therethrough, the rear extremities of said inserts provided with offset heads defining connecting bars.

5. A brake shoe consisting of a cast metal body, a plurality of inserts embedded therein and tapering toward the wearing face of the shoe, a reinforcing member consisting of superposed layers of openwork metal extending throughout the body of the shoe and receiving the said inserts therethrough, the rear extremities of said inserts provided with offset heads defining connecting bars, and a supplemental reinforcing member extending across the rear extremities of said inserts.

6. A brake shoe consisting of a cast metal body, a plurality of inserts incorporated therein and tapering toward the wearing face of the shoe and provided with longitudinally extending grooves, a plurality of superposed layers of openwork metal extending throughout the body of the shoe and surrounding the said inserts.

7. A brake shoe consisting of a cast metal body, a plurality of inserts incorporated therein and tapering toward the wearing face of the shoe and provided with longitudinally extending grooves, a plurality of superposed layers of openwork metal extending throughout the body of the shoe and surrounding the said inserts, the rear extremities of said inserts provided with offset heads.

8. A brake shoe consisting of a cast metal body, a plurality of inserts incorporated therein and tapering toward the wearing face of the shoe and provided with longitudinally extending grooves, a plurality of superposed layers of openwork metal extending throughout the body of the shoe and surrounding the said inserts, the rear extremities of said inserts provided with offset heads, and a supplemental reinforcing member extending throughout the body of the shoe and across the rear extremities of the inserts.

Signed at Mahwah, in the county of Bergen and State of New Jersey, this 30th day of December, A. D. 1916.

FITZ WILLIAM SARGENT.
